HIGH FREQUENCY ELECTRICAL SYSTEM

Application filed May 15, 1924. Serial No. 713,545.

While our invention relates generally to high frequency electrical systems, it refers particularly to a system for the reception of high frequency electrical currents.

5 A particular object of our invention is the reception of a plurality of high frequency electrical currents, either of the same or different frequencies and employing but a single collector of the high frequency currents.

10 Another object of our invention is to improve the selectivity of the reception of high frequency electrical currents; that is, to be able to receive currents of one frequency to the exclusion of currents of slightly different frequencies.

15 A further object of our invention is to provide a system in which oscillations or high frequency currents, if generated in the receiving device, will be inefficiently transferred to the collector, and will also be inefficiently dealt with upon arrival in the collector, thereby preventing the system from becoming an annoying radiator of high frequency electrical oscillations.

20 There are many conditions under which it is desirable to employ but a single collector of high frequency electrical currents to supply a number of receivers, as for instance on board ships where facilities for erecting receiving antennae as collectors of radio signals are limited, and in apartment houses and hotels where one substantial antenna on the roof of the building can be utilized by the occupants of a large number of apartments or rooms. Such a system to be satisfactory must permit the tuning of each of the independent receivers connected to the single antenna without throwing other receivers so connected out of adjustment or off 25 tune. Our intention accomplishes this requirement.

30 Selectivity, or the ability to receive signals of one frequency to the exclusion of signals of other frequencies, is a practical necessity in present day use of radio on account of the very large number of transmissions now simultaneously taking place. Our invention permits of a very high order of selectivity being obtained.

35 Some types of radio receivers are so con-

structed that if improperly handled they become generators of high frequency oscillations, and when connected to an antenna these oscillations are radiated to the great annoyance of nearby receiving systems. These 55 radiations are particularly annoying if the antenna, to which the receiver capable of generating oscillations is connected is an efficient radiator of the oscillations. Our invention utilizes an antenna or collector which 60 is so arranged as to have an inefficient transfer thereto of the oscillations generated in the receiver, and the antenna itself inefficiently handles those oscillations which are transferred, resulting in little or no effective radiation. 65

70 Our invention will be best understood by reference to the accompanying drawings in which the figures illustrate the invention employed in connection with the reception of high frequency electrical currents known as radio reception.

75 Figure 1 illustrates the invention connected directly to a regenerative type of receiver.

Figure 2, illustrates the invention inductively or indirectly coupled to a regenerative type of receiver.

80 Figure 3, illustrates the invention connected to a receiver including an amplifying system.

85 Figure 4 diagrammatically illustrates the connections for a simple unit embodying the necessary elements of the invention.

Figure 5, illustrates the manner in which the unit in Figure 4 can be employed as a 85 wave trap.

90 Referring to Figure 1 the arrangement including the coil L_1 coupled to the coil L_2 having the variable condenser C_4 in parallel therewith is generally known as a coupled rejector. Its preferred form of construction is that the coil L_2 should be wound on a tube or form having in its winding a sufficient number of turns to provide an inductance which cooperating with the capacity of 95 the condenser C_4 will provide a turnable circuit over a desired range of frequencies. The coil L_1 should comprise a small number of turns compared to coil L_2 , and should be made of relatively large wire or other construction. 100

to provide the least possible ohmic high frequency resistance, and should be closely or tightly coupled to the coil L_2 as by winding on the same form preferably immediately over the turns comprising the coil L_2 . The circuit containing the coil L_2 and condenser C_4 should have the least possible frequency resistance, and to this end it may be desirable for some frequencies to construct the coil L_2 of litzendraht wire, that is, a wire comprised of a multiplicity of insulated strands. The condenser C_4 should preferably be one of good construction having the least possible resistance and losses. The coil L_1 having low resistance and a very small number of turns, and therefore low reactance, is normally a low impedance path for high frequency electrical currents, but being tightly coupled to the tunable circuit containing the inductance L_2 and condenser C_4 , becomes a high impedance path for those frequencies corresponding to the resonant frequency or frequency adjustment of the tunable circuit. Such an arrangement will normally allow high frequency currents to freely flow through the path containing coil L_1 , but will reject with very high impedance a flow of any current of frequency corresponding to that of the resonant frequency adjustment of the tunable circuit. The terminals of the coil L_1 should preferably have heavy, low resistance wire for connection of the unit to the system in which it is to be used.

A receiver, for instance the conventional form of regenerative receiver illustrated, containing an input circuit including a variable condenser C_3 , is connected in parallel relation to the coupled rejector unit through a very small capacity condenser C_2 , the capacity of the condenser C_2 depending upon the range of frequencies with which the system deals, but always being so small as to offer a very high reactance to the flow of currents. For instance for frequencies of the order of one thousand kilocycles per second we successfully employ a condenser having the very small capacity of twenty five micro microfarads. The high reactance of this very small capacity normally obstructs the flow of currents to the receiver, diverting them to the low impedance path containing the coil L_1 , but for the frequency to which the coupled rejector is tuned the impedance of the path containing the coil L_1 becomes extremely high, and the currents for this frequency are therefore forced through the high reactance of the very small capacity condenser C_2 . Also the receiver containing the variable capacity C_3 , being tunable to the same frequency as the coupled rejector, aids in bringing the desired frequency currents through the receiver path. The receiver and rejector are coupled to the antenna or collector A through a low conductance element, such as the condenser C_1 having a very small capacity. For

a frequency of 1000 kilo-cycles we have successfully employed a condenser C_1 having a capacity of the order of twenty-five to one hundred micro micro-farads. If the antenna A is small, being only a few feet in length, and therefore of low resistance and low collective ability, a small capacity at C_1 cannot be successfully employed, but where the antenna has considerable length, as from 50 feet up, and therefore high resistance compared to the resistance of the path containing the coil L_1 , and also including good collective ability, low capacity can be very successfully employed at C_1 . The value of the capacity determines the success of the system as a collector for a plurality of receivers without material interference. The condensers C_1 and C_2 isolate the receivers from each other through their high reactance, and prevent the tuning of one from interfering with the tuning of others connected to the system. The smaller these capacities, and particularly that of condenser C_1 , the more successful is the multiple system. If resistance is employed in lieu of capacity at C_1 , the higher the resistance the more effective is the multiple reception feature. The figure illustrates how a multiplicity of receivers may be connected to the antenna A through elements C_1' and C_2' similar to the corresponding elements just described, the additional receivers being in parallel to coupled rejectors as previously described.

It is preferable that the inductive elements of the coupled rejector be screened from the inductive elements of the receiver to prevent a direct energy transfer action between these elements taking place thus by-passing the small capacity C_2 . We have indicated in Figure 1 that this may be accomplished by constructing a screen around the coupler rejector unit, preferably of thin sheet metal or wire mesh, or the same result may be accomplished by screening the inductive elements of the receiver as indicated by the dotted lines in Figure 2. A screen is not essential, as beneficial results are obtainable without screening, and a high order of efficiency in the matter of selectivity may be secured by well separating the rejector element from the receiver.

The switch S is desirable in order that when hunting for or picking up an unknown signal the rejector system may be thrown out of circuit, making the system less selective. With the switch open the hunting is accomplished through tuning the receiver as through operating the variable condenser C_3 . When the signal has been picked up and tuned to a maximum the switch S is closed and the variable condenser C_4 of the rejector system adjusted until the signal is again heard and made a maximum. When the system is properly constructed this adjustment is very sharp and makes it desirable to employ a vernier arrangement of condenser at C_4 , or one giving

small change of capacity for a large amount of motion.

Figure 2 illustrates the same system as Figure 1 except that the receiver is illustrated as having a primary circuit coupled to a secondary circuit, the selectivity system of our invention being connected to the primary instead of directly connected to the single circuit of Figure 1. The figure also illustrates that the screen to prevent direct action between the coupled rejector and the receiver may be placed about the elements in the receiver instead of about the elements of the coupled rejector as illustrated in Figure 1. The figure also illustrates that the receiver may be connected to the same ground connection as the coupled rejector.

Figure 3 illustrates the same system as illustrated in Figures 1 and 2 except that the receiver is connected to a number of stages of radio frequency amplifiers, thence to a detector for reducing the high frequency currents to low frequency currents, and thence to a low frequency amplifier for amplification of the currents in their low frequency form.

Figure 4 illustrates how the coupled rejector may be made as a simple unit having suitable capacities C_1 and C_2 , the unit being provided with binding posts B_1 , B_2 , B_3 and B_4 for connection with any desired antenna system and associated receiver.

Figure 5 illustrates the manner in which the unit of Figure 4 may be connected to an antenna and receiver to act as a wave trap. When acting as a wave trap it does not bypass all frequencies other than the desired one as in Figures 1, 2 and 3, but traps out an undesired interfering signal. By connecting the antenna A to the binding post B_4 , of Figure 4, and the receiver to the binding post B_3 , and by closing the switch S all currents are allowed to freely pass through the coil L_1 to the receiver except the particular currents to which the tunable circuit L_2 , C_4 is tuned.

Referring to any one of Figures 1, 2 and 3, it is apparent that any oscillations generated in the receiver will encounter considerable opposition to passing to the antenna A through the very small capacity, and therefore high reactance, of condenser C_2 . Such currents as do pass will be handled in an antenna far out of tune with them on account of the very small capacity of the condenser C_1 ; or if the condenser C_1 is replaced by high resistance, the antenna is equally ineffective as a radiating system of high frequency electrical currents.

We have found that with our system we are enabled to employ a number of receivers using the same antenna or collector, and can tune or adjust any one of the receivers without interfering with the tuning or adjustment of other receivers connected to the collector. We have also found that the system provides for extreme selectivity, and our experiments so

far have demonstrated that there is no serious loss of signal strength due to employing this system as compared to one employing an antenna or collector which as a whole is tuned to the receiver.

Having fully described our invention we claim:

1. A high frequency electrical system including means for collecting high frequency electrical currents and means for selectively transferring said currents to a plurality of independent receivers, each of said means comprising a single high reactance element connecting said collector and a receiver through a single connection, and a low resistance, low reactance path shunting said connecting element and receiver, a closed tunable circuit, and a tight electrical coupling between said closed tunable circuit and the reactance element of said path each of said receivers operating independently with respect to each other.

2. A high frequency electrical system including means for collecting high frequency electrical currents and means for selectively transferring said currents to a plurality of independent receivers, each of said means comprising a condenser of small capacity connecting said collector and a receiver through a single wire connection, and a low resistance, low reactance path shunting said condenser and receiver, a closed tunable circuit, and a tight electrical coupling between said closed tunable circuit and the reactance element of said path each of said receivers operating independently with respect to each other.

3. A high frequency electrical system including means for collecting high frequency electrical currents, and means for selectively transferring said currents to a plurality of independent receivers, each of said transferring means comprising a high reactance element connecting said collector and a receiver through a single wire connection, and a coupled rejector connected in parallel with said connecting element and receiver said rejector including an inductance shunted by a capacity, said inductance being coupled to a circuit in parallel with said element and said receiver, said receivers being capable of independent operation without mutual reaction one upon the other.

4. A high frequency electrical system including means for collecting high frequency electrical currents and means for selectively transferring said currents to a plurality of independent receivers, each of said transferring means comprising a condenser of small capacity connecting said collector and a receiver through a single wire connection and a coupled rejector shunting said condenser and receiver, said coupled rejector including an inductance and capacity adjusted to the frequency desired to be received by said receiver, each of said receivers being capable of inde-

pendent operation without mutual reaction one upon the other.

5. A high frequency electrical system including means for collecting high frequency electrical currents for distribution to a plurality of receivers, a low conductance element in circuit with said collector, said element coupling said collector to a receiver and ground through a single wire connection containing a high reactance element and to ground through a coupled rejector said rejector when tuned to the desired frequency offering a high impedance thereto for reflecting said desired frequency into said high reactance element.

6. A high frequency electrical system including means for collecting high frequency electrical currents for distribution to a plurality of receivers, a condenser of small capacity in circuit with said collector, a receiver, a ground connection, said condenser coupling said collector to said receiver and ground through a single wire connection containing a high reactance element and to ground through a coupled rejector said rejector when tuned to the desired frequency offering a high impedance thereto for reflecting said desired frequency into said high reactance element for selectively operating any one of said receivers without reaction one upon another.

7. A high frequency electrical system including means for collecting high frequency electrical currents for distribution to a plurality of receivers, a low conductance element in circuit with said collector, said element coupling said collector to a receiver and ground through a single wire connection including a condenser of small capacity and to ground through a coupled rejector said rejector when tuned to a desired frequency offering a high impedance thereto for bypassing the desired frequency through the associated receiver for operation of any one of said receivers without reaction one upon another.

8. A high frequency electrical system including a collector of high frequency electrical currents and a plurality of receivers connected thereto each through the following arrangement: a condenser of small capacity and a divided path, one division including a single wire connection containing a condenser of small capacity and a receiver in series, and the other division containing a coupled rejector.

9. A system for receiving a plurality of independent signals on a single antenna comprising individual means for loosely coupling a plurality of independent receivers to said antenna said receivers being tunable to selected ones of said signals and means bypassing each of said coupling means and the corresponding receiver comprising a circuit offering a high impedance to the selected fre-

quency and a low impedance to all other frequencies.

10. A carrier wave receiving system comprising a single collector of said waves and a plurality of independently operable receiving stations connected to said collector, each of said receiving stations comprising a path to ground for said collector including capacity and inductance in series therewith, a receiver capacitatively connected to a point between the first mentioned capacity and said inductance said receiver having a circuit tuned to the desired frequency, and a closed circuit tuned to said frequency closely coupled to said inductance.

11. A carrier wave receiving system as defined in claim 10, and means for shielding each receiver from its corresponding grounding inductance and closed tuned circuit.

12. The method of actuating a plurality of independently tunable radio receivers by energy from a single collector which comprises the steps of grounding said collector at each receiving station through a tunable circuit loosely coupled to said collector, connecting a receiver to each of said grounding circuits through a small capacity, tuning one or more of said receivers to desired frequencies and tuning the corresponding grounding circuits to the said desired frequencies, respectively.
